UNITED STATES PATENT OFFICE.

DAVID MAYER, OF HARTFORD, CONNECTICUT.

DESIGN FOR A SPOON, &c.

SPECIFICATION forming part of Design No. 20,904, dated June 30, 1891.

Application filed May 25, 1891. Serial No. 394,064. Term of patent 3½ years.

To all whom it may concern:

Be it known that I, DAVID MAYER, a citizen of the United States, residing at Hartford, in the county of Hartford and State of Connecticut, have invented and produced a new and original Design for Spoons and the Like Articles, of which the following is a specification, reference being had to the accompanying drawing, forming a part thereof.

- 10 The figure is a view in elevation of a spoon, illustrating the embodiment of my design. The leading feature of the design consists of a spoon or like utensil, the handle part comprising a statue in miniature of Jonathan 15 Trumbull, the figure being located on the end and in line with the handle of the spoon, while from the base of the statuette the handle extends to the shank and bowl and broadens into the bowl form, making up a spoon, the 20 whole constituting a novel design.

In the accompanying drawing, the letter *a* denotes the handle of the spoon, *b* the statu-

ette, and *c* the bowl of the spoon, that being the article selected for the representation of the embodiment of my design.

The spoon or like article may be formed of any suitable material, as silver or other precious metal, or of the baser metals sometimes employed in the making of such articles, and the handle is provided with spaces for the introduction of any suitable dates or inscriptions. The name "Brother Jonathan" appears at the base of the statuette, and it or any other suitable inscription may be employed.

25 30 35 I claim as my invention—

The design for a spoon or the like article, comprising a handle formed in part by and terminating with a statue of Jonathan Trumbull, as described and shown.

DAVID MAYER.
